(57) **CLAIM**

The ornamental design for a faucet kit as shown and described.

DESCRIPTION

FIG. 1 is a perspective view of a first embodiment of a faucet kit showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1;

FIG. 10 is an enlarged view of portion 10 shown in FIG. 1;

FIG. 11 is an enlarged view of portion 11 shown in FIG. 3;

FIG. 12 is an enlarged view of portion 12 shown in FIG. 3;

FIG. 13 is an enlarged view of portion 13 shown in FIG. 5;

FIG. 14 is an enlarged view of portion 14 shown in FIG. 8;

FIG. 15 is a perspective view of a second embodiment of the faucet kit;

FIG. 16 is another perspective view thereof;

FIG. 17 is a front elevational view thereof;

FIG. 18 is a rear elevational view thereof;

FIG. 19 is a left side elevational view thereof;

FIG. 20 is a right side elevational view thereof;

FIG. 21 is a top plan view thereof;

FIG. 22 is a bottom plan view thereof;

FIG. 23 is an enlarged view of portion 23 shown in FIG. 15;

FIG. 24 is an enlarged view of portion 24 shown in FIG. 15;

FIG. 25 is an enlarged view of portion 25 shown in FIG. 17;

FIG. 26 is an enlarged view of portion 26 shown in FIG. 17;

FIG. 27 is an enlarged view of portion 27 shown in FIG. 19;

and,

FIG. 28 is an enlarged view of portion 28 shown in FIG. 22.

The dash-dash broken lines in the drawings depict portions of the faucet kit that form no part of the claimed design. The dot-dash broken lines in FIGS. 1, 3, 5, 8-15, 17, 19 and

(Continued)

22-28 represent boundaries of the enlarged portions and form no part of the claimed design.

1 Claim, 28 Drawing Sheets
